UNITED STATES PATENT OFFICE

WILLIAM B. ALLBRIGHT, OF CHICAGO, ILLINOIS, ASSIGNOR TO ALLBRIGHT-NELL COMPANY, OF CHICAGO, ILLINOIS, A CORPORATION OF ILLINOIS

WASHER

Application filed March 14, 1928. Serial No. 261,524.

This invention relates to washers, and more particularly to improved forms of machines for washing and cleaning certain animal parts and packing house products.

5 A primary object of my invention is to provide an improved washing machine especially adapted for the effective and expeditious cleaning of animal parts without substantial injury thereto.

10 Another object of this invention is to provide an improved washing machine comprising a rotatable drum presenting a cleaning surface of greater extent than the external circumference of the drum.

15 A further object of my invention is to provide a washing machine whereby the parts to be cleaned are subjected to a compound scraping and rubbing action.

A still further object of the invention is 20 to provide an improved washing machine which is comparatively simple in construction, effective in operation, and which is adapted to thoroughly clean a large number of parts in a comparatively short time. With 25 these objects in view, as well as others that will become apparent from the following disclosure, reference will now be had to the accompanying drawings forming part of the same, and in which—

30 Figure 1 is a front elevational view of a preferred embodiment of my invention.

Figure 2 is an end elevational view of the form of invention shown in Figure 1.

Figure 3 is a view similar to Figure 2 of 35 the opposite end of the machine.

Figure 4 is a top plan view of the drive end head used in the form of invention shown in Figure 1.

Figure 5 is a side view of the head shown 40 in Figure 4.

Figure 6 is an edge view of the head shown in Figure 5.

Figure 7 is a top plan view of the discharge end head.

45 Figure 8 is a side elevational view of the structure shown in Figure 7.

Figure 9 is a side elevation of one of the hood heads.

50 Figure 10 is an edge view of the structure shown in Figure 9.

Figure 11 is a top plan view of the structure shown in Figure 9.

Figure 12 is a side elevational view of one of the cylinder heads.

Figure 13 is an edge view thereof.

Figure 14 is a front elevational view of one of the bearing caps used with the invention.

Figure 15 is a side view of the construction shown in Figure 14.

Figure 16 is a plan view of one of the perforated drum sections utilized in developed form.

Figure 17 is a similar view of the drum gate, and

Figure 18 is an enlarged fragmental sectional view through the material forming the cylinder and particularly disclosing the apertures and scraping sections or burs therein.

Referring to the drawings by reference characters in which like characters designate like parts, 10 designates a drive end head which as shown in Figures 1, 2, 4, 5 and 6 comprises a semi-circular plate member 11, 75 provided with a plane outwardly extending flange 12, and a curved flange 13 co-extensive within the flange 12 and substantially widened intermediate its ends as indicated at 14. Flange 14 is provided with a plurality of 80 apertures 15 for the reception of securing elements 16 which extend through flanges 17 of a pair of leg members 18 for rigidly securing head 10 and leg members 18 together. Flange 12 intermediate the ends thereof is 85 widened as indicated at 19, co-extensive with widened portions 14 and formed in widened portions 19 is a bearing 21. Integrally connecting widened portion 14 and bearing 21 90 is a plurality of radiating reinforcing ribs 22.

The opposite end head 23 is similar in construction to end head 10, and to the widened portion 14 of which a pair of leg members 24 are secured by securing bolts 16. Curved flanges 13 of end heads 10 and 23 are provided with a plurality of apertures 25 for the reception of suitable securing elements which extend through and rigidly secure the oppo- 100

site ends of a semi-cylindrical casing 26 to end heads 10 and 23.

Supported on and secured to flanges 12 of end heads 10 and 23 are the plane flanges 27 of hood heads 28, which as shown in Figures 9, 10 and 11, are quadrant shaped and are provided with apertured curved flanges 29, reinforcing ribs 31, and bearing cap receiving portions 32. The opposite ends of a casing section 33 are rigidly secured to flanges 29 by suitable securing devices extending through casing section 33 and apertures 34 in flanges 29. Bearing caps 35 are secured to widened portions 19 of flanges 12 by suitable securing elements 36 and each cap is provided with a lubricating duct 37 for lubricating the opposite ends of a drum drive shaft 38 which are journaled in bearings 21 and caps 35.

20 Formed integrally with head 10 is a bearing 39 in which is mounted a stub shaft 41 on which is journaled a sprocket wheel 42. Secured to sprocket wheel 42 by securing bolts 43 is the hub 44 of a pinion 45 which 25 meshes with a gear 46 fixed to one end of drum drive shaft 38. End head 10 is provided with a threaded boss 47 and corresponding hood head 28 is provided with a similar boss 48, said bosses receiving securing elements extending through ears 49 and 51 of a gear and pinion housing 52, which as shown in Figure 1 is spaced from adjacent heads 10 and 28 to provide room for a sprocket chain 53 which extends about 30 sprocket wheel 42 and a similar sprocket wheel 54 secured to shaft 55 of an electric motor 56 which is secured to a suitable support 57 on casing 33. Bearing cap 35 at the discharge end of the machine is provided 35 with a grease cup 58 while the duct 37 in cap 35 at the drive end of the machine has threaded therein to the end of a tube 59, the outer end of which is supported by a clip 61 carried by ear 51 and a suitable grease cup 62 40 is carried by the outer end of tube 59. A grease cup 63 is attached to stub shaft 41 for lubricating sprocket wheel 42 through a duct 64.

Connected into end head 23 as at 65 is a 50 water pipe 66 which has in communication therewith outward of connection 65 a steam pipe 67. Water pipe 66 is provided with a valve 68 outward of the connection of steam pipe 67 therewith and steam pipe 67 is provided with a valve 69 by means of which 55 valves water is admitted into the chamber defined by end heads 10 and 23 and casing 26 at any desired temperature regulated by the amount of steam admitted with the water.

60 Casing 26 is depressed to form a downwardly inclined discharge trough 71, or if desired trough 71 may be separate from casing 26 and may be secured thereto by any suitable means. Secured to flange 14 and an 65 extension 72 of trough 71 is a casting 73 pro-

vided with a vertically slidable gate 74 which is controlled by a bell crank lever 75 pivoted as at 76 and having a lost motion pivotal connection 77 with gate 74, lever 75 being provided with a suitable operating handle 78. A hood 79 of substantially quadrant shape in side elevation and comprising sides 81 and a curved face or cover portion 82 is pivotally supported in grooves 83 in bearing caps 35 to permit a swinging movement of hood 79 to open and close the interior of the washer. Hood 79 is provided with a pair of manipulating handles 84 and the sides 81 thereof rest substantially in contact with the opposing faces of end heads 10 and 23 and hood heads 28 as indicated by dotted lines in Figures 2 and 3, and hood 79 is further provided with a flange 85 adapted in closed position thereof to abut a flange 86 secured to casing 26 and adapted in open position thereof to abut a flange 87 secured to casing 33. End heads 10 and 23, hood heads 28, casings 26 and 33 and hood 79 define a closed cylindrical chamber in which is disposed a drum 88 for receiving the material to be washed or cleaned.

20 Drum 88 comprises a pair of heads 89, each of which as shown in Figures 12 and 13 comprises a plate 91 provided with a laterally extending flange 92 which as is clearly shown in Figure 12 is of uniform wave-like formation and integrally connecting plate 91, flange 92 and a central hub member 93 are a plurality of radially extending reinforcing ribs 94'. Heads 89 have the hub members 93 thereof fixed to shaft 38 for rotation therewith and secured to flanges 92 are the opposite ends of a sectional casing 94, which when assembled is of wave-like form corresponding to that of flange 92 as clearly indicated in Figure 3.

Casing 94 is formed of a plurality of sections 95 which have their ends secured to flanges 92 and have their sides outwardly turned to provide flanges 96 which flanges are secured together in abutting relation by securing means 97 as indicated in Figure 3, thus providing the complete scalloped or wave-like drum 88. Casing 94 is interrupted at a point opposite hood 79 and is provided with a removable section or gate 98 so that upon opening hood 79 access can be had to the interior of drum 88 through section or gate 98.

110 Each section 95 and gate 98 are of a formous construction which are formed by punching out portions of the metal to form apertures 99 in such fashion that a bur 101 is formed projecting from one side of the sheet of metal inward about each aperture 99. The apertures are disposed relatively close to one another so that the burs form a rough surface. While burs 101 form a rough scraping surface the inner ends thereof are slightly rounded as indicated at 102 (Figure 130

18) in order to prevent sharp cutting surfaces which would be apt to injure the parts being treated.

In the operation of the machine a suitable number of animal parts to be washed or cleaned are disposed within the drum 88 upon opening hood 79 and gate 98, for example parts such as beef and hog stomachs being turned inside out to expose the side bearing the tenacious material, after which gate 98 and hood 79 are closed. Water is then admitted into the chamber surrounding the drum 88 through valve 68 and a desired amount of steam is admitted with the water through valve 69 whereupon motor 56 is set into operation which through the sprocket 54, chain 53, sprocket 42, pinion 45, gear 46, and shaft 38 imparts rotation to drum 88, which due to the successive reduction drive connections is rotated slowly as compared to the rotation of motor shaft 55.

Upon the rotation of drum 88 the animal parts will be carried forwardly and upwardly by the combined action of burs 101 and the wave formation in casing 94 to a point where the angle of the supporting portions of burs 101 and wave formations is such that the parts will fall therefrom or slide down over the rough wave-like surfaces. In this repeated movement the parts are subjected to an abrading or scraping action from burs 101 and the wave-like surfaces which scrapes off portions of the viscous membrane which it is desired to remove. Furthermore the continuous rotation of drum 88 by means of burs 101 and the wave like surfaces will cause a compound scraping action on the parts which tend to remain in the lower portions of the wave sections of the drum. Furthermore by providing the drum with a wave-like or scallop formation the parts are brought into contact with a larger abrading surface than if the drum were of cylindrical formation. From time to time gate 74 may be opened to allow the water to pass through trough 71 so as to flush out the sticky detached material.

From the foregoing disclosure it will be seen that a washing machine is provided which due to the novel formation of the revolvable drum is capable of cleaning a large number of animal parts efficiently and in a comparatively short period of time.

While I have disclosed but a single embodiment of my invention, it is to be understood that I am not limited thereto, but am at liberty to make such changes or alterations as fairly fall within the scope of the appended claims. Accordingly, what I claim and desire to secure by Letters Patent is:

60 1. A machine for cleansing materials comprising a pair of semi-circular end heads, supporting legs secured to said heads, a semi-cylindrical casing secured to said heads, a pair of sector shaped heads secured to each 65 of said first heads; a casing section secured

to said last heads; co-operating bearings and bearing caps supported by said first heads, a hood revolvably supported by said bearing caps; a shaft supported in said bearings; a sinuous foraminous revolvable drum secured 70 to said shaft; and means for imparting rotation to said shaft.

2. A machine for cleansing and scraping animal tissues or similar materials, comprising a casing, a revolvable drum mounted for 75 rotation within said casing and adapted to receive said materials, the walls of said drum being constructed of sinuous foraminous material the foraminations being formed so as to provide scraping projections extending 80 toward the axis of said drum, the sinuous form of said drum being such as to provide wide grooves separated by ridges of relatively great width so that the material will be caused to successively enter said grooves and 85 be moved over said ridges and scraped by said projections as said drum is being rotated.

3. A machine for cleansing and scraping animal tissues or similar materials comprising a casing, a drum mounted for rotation in 90 said casing and adapted to receive the materials to be cleansed and scraped, said drum being provided with a multiplicity of openings extending through its side walls, said side walls being longitudinally corrugated 95 to provide alternate grooves and ridges of relatively great width compared to the diameter of said drum, whereby said materials are caused to successively enter said grooves and slide over said ribs and to be scraped and 100 cleansed by the relatively sharp corners provided by said openings in said drum.

In testimony whereof I affix my signature.

WILLIAM B. ALLBRIGHT.
